UNITED STATES PATENT OFFICE.

JOHN P. BROADMEADOW, OF BRIDGEPORT, CONNECTICUT, ASSIGNOR TO HIMSELF AND ALBERT EAMES, OF SAME PLACE.

IMPROVEMENT IN MOLDING FOR METAL CASTINGS.

Specification forming part of Letters Patent No. 26,321, dated November 29, 1859.

To all whom it may concern:

Be it known that I, JOHN P. BROADMEADOW, of Bridgeport, in the county of Fairfield and State of Connecticut, have made certain new and useful Improvements in Foundry Machinery; and I do hereby declare that the following is a full, clear, and exact description of the same, reference being had to the accompanying drawings, which form part of this specification, and in which—

Figure 1 represents a front elevation of the press used by me in practicing my invention. Fig. 2 is a side elevation of the same, and Fig. 3 represents a vertical transverse section through the center of the same. Fig. 4 represents a vertical longitudinal section of a cope of the flask, patterns and their appurtenances, and the sand ready for pressing. Fig. 5 is a plan of the cope-plate, and Fig. 6 is a plan of the cope and patterns. Fig. 7 is a side view of the strike. Fig. 8 represents a vertical longitudinal section of the drag of the flask, the patterns and their appurtenances ready for pressing. Fig. 9 is a plan of the bottom plate, and Fig. 10 is a plan of the drag and patterns. Fig. 11 represents a vertical longitudinal section of a complete mold ready for pouring. Fig. 12 represents a vertical longitudinal section of a drag, pattern, and their appurtenances; and Fig. 13 is a plan of the drag and pattern.

My invention relates to the formation of sand molds for casting by means of mechanical devices, so as to supersede the hand-labor usually required in ramming the sand; and it has reference particularly to what is technically called "snap-flask molding," or the formation of sand molds in flasks so constructed that they are removable from the molds before the metal is poured in. The advantages of this kind of molding for small articles have long been known, as it permits a number of molds to be formed by the use of a single flask, and my improvements enable the molds to be formed with greater precision and with much less labor than has heretofore been possible, thus insuring better castings at a less cost.

Before proceeding to describe my improvements it is proper to state that I do not pretend to be the first that has substituted mechanical pressure for hand-ramming in the

formation of sand molds, nor to be the originator of snap-flask molding; but I believe that I have so simplified the machinery and process of sand-molding by machinery as to render it practically valuable for ordinary foundry purposes.

My invention by which this result is attained is divided into several parts, the first part of which consists in the combined use of a half-flask of sufficient size to contain the quantity of loose sand required to form a half-mold, with a follow-board small enough to enter freely into the said half-flask and act as a piston to compress the sand when proper pressure is applied, so that the half-flask not only performs the usual duty of containing the rammed sand or mold, but also acts as a measure to determine the quantity of loose sand which is to be rammed or pressed. This part of my invention possesses an advantage over preceding inventions in mechanical sand-molding—such, for example, as that of Chapman Warner—in dispensing with the use of a hopper or other measure of the sand separate from the flask, and consequently permits the molding to be accomplished with greater speed and less complex mechanism.

The special object of the second part of my invention is to insure the equable ramming or pressing of the sand by the operation of the follow-board; and it consists in the combined use of a strike whose profile is substantially the same as that of the pattern, and of the half-flask above described, so that by the operation of the former definite portions of the loose sand in the latter can be removed from above the protuberant portions of the patterns previous to compression.

The special object of the third part of my invention is to insure the retention of the sand in the cope of the flask when it is lifted from the match-board; and it consists in the combined use of a ribbed cope-plate of the half-flask that constitutes the cope, and of pins in the said cope that sustain the cope-plate, the said cope-plate being small enough to enter into the cope, so that the weight of the sand adhering to the ribs of the cope-plate when the latter is depressed into the flask is transferred by the sustaining-pins to the cope.

The special object of the fourth part of my

invention is to insure the integrity of the mold (after the snap-flask is removed) during the pouring of the metal; and it consists in the combined use of a bottom plate of a size to pass into the lower half-flask, or "drag," as it is technically termed, of the aforesaid cope-plate, and of clamps that connect the cope-plate and bottom plate together after the snap-flask is removed. This part of my invention dispenses with the employment of the weights generally used in snap-flask molding to prevent the cope from being raised by the pressure of the melted metal.

The special object of the fifth part of my invention is the mechanical formation of the sprue through which the melted metal is poured into the mold; and it consists in combining the sprue-pattern with the follow-board, so that the former is retained in its proper position during the mechanical ramming or pressing of the sand, and using these in connection with a match-board having an opening through it to receive the lower end of the sprue-pattern and permit its descent when the pressure is applied.

The special object of the sixth part of my invention is to insure the equable compression of the sand of the mold in articles of such a form that a profile-strike cannot be employed with advantage; and it consists in the combined use of a follow-board having suitable projections or depressions, or both, thereupon, in connection with a plain half-flask, by which I mean one with straight sides, such as above specified, in contradistinction to the plans previously in use, in which the half-flask is furnished with projections or indentations. This part of my invention is important, as it permits the application of mechanical molding to a great variety of objects which cannot be molded by the use of the flasks having projections and depressions, hitherto used in mechanical molding.

The accompanying drawings illustrate my invention. In carrying it into effect I am enabled, from the nature of my improvements, to make use of a simple lever-press, which, although not possessing any special novelty, is, from its simplicity, admirably adapted to foundry purposes. In this press the head-plate A is connected with the frame B of the press by means of a pair of standards, C C. The frame sustains the movable platen D, which is secured to the upper end of a pair of slides, E E, that move in suitable guides formed in the cross-beams of the frame. The platen bears upon a strut, F, whose lower end rests upon a ball formed on the outer extremity of the arm G. This arm projects from a rock-shaft, H, that extends through and is supported by the standards of the frame B of the press, and has a lever-handle, I, secured to one of its outer ends, the arrangement of the whole being such that when the lever-handle I is drawn forward the platen D is caused to approach the head-plate A. The

frame B of the press has a pair of ways, J J, secured to it, which extend on either side of the platen D, and a carriage, K, is constructed to slide to and fro on these ways, so that objects placed thereon may be entered between the platen and the head-plate and may be withdrawn therefrom.

The flasks which I prefer to use are snap-flasks made in two halves or parts—a cope, L, and a drag, M—each being constructed with a hinge, a, at one corner and a latch, b, at the diagonally opposite corner. Each of these half-flasks is of sufficient capacity to hold the quantity of loose sand required to form a half-mold. The two halves are fitted with guide-pins and holes in the usual manner, so that they may be applied exactly to each other when the two halves of the mold are put together.

When an article similar to a roller is to be molded, the pattern is made in two halves in the usual manner, and each one of these halves is secured to a match-plate which forms the base on which the sand is compressed. The match-plate N, that is to be used in connection with the cope L, is furnished with holes similar to those in the drag to receive the guide-pins of the cope. The match-plate O, that is to be used in connection with the drag M, is furnished with guide-pins similar to those of the cope L. The drag match-plate has also secured to it the pattern c of the gates, through which the melted metal passes into the molds from the sprue. The drag is used in connection with a follow-board, P, (battened on its upper side,) of such size as to pass easily into it, so as to act as a piston and compress the sand. The cope is also used in connection with a follow-board, R, similar to the drag follow-board, of sufficient size to pass easily into the cope, and fitted with the sprue-pattern S, which is made fast to it. The cope match-board N is perforated to permit the end of this sprue-pattern to pass through, as shown in section at Figs. 3 and 4. Both match-boards are furnished with battens, which are fitted to enter into the frame of the carriage K of the press, so as to hold the match-board in place.

A cope-plate is used in connection with the cope L. This cope-plate f has a series of bars, e e, extending from that one of its faces which is next the sand. The cope L, moreover, is fitted with lateral sustaining-pins i, in such positions that when the sand is compressed by the forcing down of the cope-plate the latter rests upon these pins. A bottom plate, g, is used in connection with the drag, and when articles similar to rollers, or, in other words, that extend in line either across or lengthwise with the flask, are used, a strike, T, having a profile similar to that of the pattern is prepared.

When the flasks, patterns, &c., have been prepared as above described, molding is effected in the following manner: The match-board N of one of the parts of the flask—the

cope, for example—is placed upon the carriage K of the press and the cope L is applied to it. Tempered sand is then sifted into the cope upon the patterns, in the manner usually followed in molding by hand. When the patterns are covered, the remainder of the flask is filled with loose tempered sand previously sifted, after which the surplus sand projecting above the rim of the cope is struck off with the straight edge of the strike, Fig. 7. The profile edge of the strike is then drawn across the surface of the sand to remove portions thereof over the two patterns. The operator now applies the cope-plate f, which should have been previously brushed with clay-water to make the sand adhere, and lastly applies the follow-board R, entering the sprue-pattern S in the hole of the match-board. He then shoves the press-carriage, with the flask and its appurtenances, beneath the head-plate A, and, applying his hand to the lever-handle I, forces the plate upward. The platen, in rising, passes through the carriage-frame and bears against the battens of the match-board, raising it with the flask and appurtenances, and bringing the follow-board R in contact with the head-plate of the press. The pressure produced by the continued movement of the lever-handle forces the cope-plate and follow-board to enter into the cope, thus compressing the sand therein. The movement of the lever-handle is continued until the cope-plate reaches the sustaining-pins, which is easily known by the position of the follow-board, after which the lever-handle is let back, thus permitting the platen to descend and drop the match-board, with the flask, &c., upon the carriage. The latter is now drawn forward, and the follow-board is rapped lightly and withdrawn. The match-board is then rapped and the cope is lifted from it. This operation is effected without danger of the sand falling out, as the compressed sand adheres to and is sustained by the bars of the cope-plate, and the latter, with the adhering sand, is carried by the cope through the invention of the sustaining-pins *i i*. The cope is then set on its side until the drag is molded, which is effected in the same manner. Then the drag is reversed with its match-plate, the latter is rapped and withdrawn, and the drag is carried to the part of the molding-floor where the mold is to be poured. After it is set down the cope is applied to it, and if the patterns and match-boards have been properly made in the usual manner the two parts of the mold apply themselves perfectly to each other by entering the guide-pins of the cope into the holes in the drag. After the two parts of the flask are in place, the latches are loosed and the parts of the flask are opened and removed, leaving the mold between the bottom plate, g, Fig. 11, and the cope-plate f. Clamps *j j* are then applied to hold these two together, and are conveniently made secure by wooden wedges s, after which the mold may be poured. As soon as the snap-flask is re-

moved its parts may be used, in connection with the match-boards, the follow-boards, and other bottom cope-plates, to form new molds, so that the same flask answers for a large number of molds.

In order to prevent any risk of the bursting of the mold by lateral pressure, it is expedient to introduce into each part of the flask, before the sand is thrown in, a ring-plate, t, which embraces the mold during casting.

In the preceding description I have supposed the article to be molded to be a roller extending for some distance through the flask without change of section, so that the profile-strike can be readily used.

When the sections of the article at different parts of its length are different, a follow-board or a cope-plate with projections or indentations, or both, corresponding with the projections or indentations in the pattern is used to insure the equality of the pressing of the sand. An example of such use is shown at Figs. 12 and 13, where the article, V, to be molded is hub with a broad flange. In this case the follow-board P has projections o and an indentation, w, thereon corresponding with the form of the pattern.

As articles to be molded present an indefinite variety of forms, it is not possible to furnish a precise rule for determining the exact form of the strike and follow-board to suit all cases that may arise; and as trial only can determine the best form, it is sufficient to indicate the principle of their construction, which is that they must correspond in general form with the patterns. If on trial of a new strike the sand is found to be too tightly packed over the pattern, a strike having a more protuberant profile must be substituted; and if the sand is found to be too loosely packed over the pattern the profile of the strike is too protuberant. The same is true of the follow-board.

Having thus described my apparatus, what I claim as my invention, and desire to secure by Letters Patent, is—

1. The combined use of a half-flask of a sufficient size to hold the quantity of loose sand required to form a half-mold, and of a follow-board small enough to enter the said half-flask and act as a piston to compress the sand therein when pressure is applied, substantially as herein set forth.

2. The combined use of a half-flask, as above described, and of a strike whose profile corresponds in form with the transverse section or profile of the pattern, substantially as herein set forth.

3. The combined use of a half-flask, as above described, constituting the cope, of a ribbed cope-plate fitted to enter therein, and of sustaining-pins in the said cope, the whole operating substantially as herein set forth.

4. The combined use of the aforesaid cope-plate, of a bottom plate fitted to enter the drag of the flask, and of clamps, substantially as herein set forth.

5. Combining the sprue-pattern with the follow-board, when this combination is used in connection with a match-board having an opening to permit the descent of the lower end of the sprue-pattern, substantially as herein set forth.

6. The combination of projections or indentations, or both, with the follow-board, in con-

tradistinction to constructing the flasks with projections and indentations.

In testimony whereof I have hereunto subscribed my name.

JOHN P. BROADMEADOW.
